FALSEWORK GIRDER

Otto Hinze, Hannover-Kleefeld, Germany, assignor to
Hico Corporation of America, New York, N.Y.
Filed June 1, 1961, Ser. No. 114,215

Claims priority, application Germany June 7, 1960
13 Claims. (Cl. 189—37)

The invention concerns a method of producing falsework girders, preferably telescopic falsework girders, and falsework girders produced by means of this method.

According to one feature of the present invention there is provided a method of producing falsework girders or girder portions especially telescopic falsework girders comprising at least one outer and inner girder adapted to be telescoped one in the other, which are adapted to be locked with one another by means of a catch element, characterised by arranging concentrations of material at the flange-like upper webs and lower webs of the girder or girder portions.

According to another feature of the present invention there is provided a falsework girder, preferably telescopic falsework girder comprising at least one outer and inner girder adapted to be telescoped one in the other the girder or the inner and outer girder having concentrations of material at the flange-like upper webs and the lower webs.

In a preferred embodiment the invention concerns a telescopic falsework girder comprising at least an outer and inner girder each adapted to be slidably disposed one in the other, which are adapted to be locked relative to one another in any extended position by means of a fastener e.g. a cotter.

In an embodiment of the girder comprising an outer and an inner girder supporting brackets are arranged on the outer ends of both girder portions. However it is possible to use an outer girder with two inner girders which are displaceably mounted on the ends thereof or an inner girder with two outer girders which are displaceably mounted on the ends of the inner girder. In those alternative embodiments supporting brackets are provided at least one the extendible girder ends. Besides cotters, screws, eccentrics or similar clamping means are known and can be used as the fastener.

It is known moreover to impart to the girder during production or before being laid a camber corresponding to the deflection expected when loaded. The arrangement of such a camber can be provided in special embodiments of the girder in accordance with the invention.

Telescopic falsework girders have hitherto been made practically without exception of steel and constructed in the form of solid-webbed and lattice girder or as a mixture of systems, in which solid-webbed and lattice elements are used alternately.

Known solid-webbed girders are either made of rolled or folded sheet and have uniform thickness of material. It is known moreover to weld together solid-webbed girders of individual profiles. Cup-shaped or triangular profiles are thus used for the upper flange, whilst the lower flange in most cases consists of angle and round steel.

Lattice girders are more difficult to make owing to necessary weld connections between the flanges and the web members.

Production of these known falsework girders is comparatively expensive because considerable manual labour or extensive mechanical production equipment is required.

Attempts to introduce a falsework girder of light metal constructed of tubular profiles having a circular cross-section was not successful because such girders are not equal to the requirements demanded therefrom. With

2

the small tolerances even slight deformations or denting lead to jamming of the girder sections slid one in the other. Moreover considerable deflections made intermediate supports at comparatively short intervals necessary.

The invention is based on the problem to provide a novel kind of girder which, for example, improves girders of steel and also makes it possible for them to be constructed from other materials. This problem is tackled in accordance with the invention by the fact that the girder or girder section is cast by arranging concentrations of material at the upper flange and lower flange.

In accordance with a preferred embodiment the girders or girder sections are extruded whilst simultaneously material is displaced at the upper flange and the lower flange.

In accordance with a preferred embodiment the girders or the girder sections are made from plastics material, in this connection it is advantageous to embed inserts of extension resisting material in the concentrations of material of the lower flange at least.

The invention includes the manufacture of the girder or the girder sections of metal, preferably light metal, by arranging concentrations of material in the upper flange and the lower flange. In accordance with the invention girders or girder sections are made from steel, for example.

The method of production in accordance with the invention leads to surprising price reduction of the girder, whereby more especially by the concentration of material at certain points, girder constructions are obtainable which in respect to material properties have greatly increased resistance to extension.

The falsework girder produced in accordance with the method is distinguished by the construction of the girder or the inner or outer girder of extruded sections having material concentrations in upper flange and the lower flange. This results in a construction of low weight since the material is arranged at the points where forces occur, i.e. compressive forces in the upper flange and tensile forces in the lower flange. The webs of the sidewalls have the minimum wall thickness necessary to avoid denting.

When arranging the material agglomerations in the region of the upper and lower flanges a preferred embodiment of the invention provides that the agglomeration in the region of the upper flange amounts to 10% more than in the region of the lower flange.

In accordance with a particularly preferred embodiment of a telescopic falsework girder the girder sections, i.e. at least at an outer and at least at an inner girder in the region of the upper web or upper flange there are provided two sliding surfaces complementing one another for the load transmission.

In accordance with a particularly preferred embodiment of the invention the sliding surfaces are provided in material concentrations in the upper flange. With advantage the sliding surfaces and the material concentration in the region of the upper flange are spaced apart. With such distribution of the masses there is obtained a particularly favourable resistance against lateral forces. In this embodiment the invention provides for the sliding surfaces provided with material concentrations to be inclined outwards and downwards on either side of the longitudinal centre plane of the girder.

Herewith there is provided a telescopic girder the outer and inner girder of which are supported on sections of sliding surfaces each forming a key, the upper flanges of the outer and inner girder are kept free of the forces transmitted between these girders and, for example, guided free of contact one against the other. The key-like arrangement of the sliding surfaces on either side of the

longitudinal centre plane thus causes a centering of the outer and inner girder, besides the lower flanges being centered relative to one another, at the same time.

The angle of the sliding surfaces is advantageously so dimensioned that, seen in cross-section, only compressive forces occur in the upper web of the inner girder. A further construction of the invention provides that the forces extending in all sections of the inner girder in the transverse plane are compressive forces exclusively.

The sliding surfaces of the inner and outer girder are preferably arranged on either side of the longitudinal centre plane and beneath a horizontal plane determined by the upper flange of the girder section concerned, and the angle of the sliding surfaces is so dimensioned that the components of the resulting forces in the transverse direction of the girder in the flange-like upper web produce compressive forces. The inner girder is preferably constructed with Y-shaped webs beneath the flange-like upper web, the sliding surfaces being disposed at the upper ends of the V-shaped portion of the webs.

The angle of inclination of the sliding surfaces is conveniently disposed between 45° and 10° relative to the horizontal. This angle of inclination is preferably limited between 40° and 20° relative to the horizontal. The preferred embodiment has an angle of about 30° relative to the horizontal.

A girder in accordance with the invention may be made of steel. With particular advantage however a feature of the invention provides a construction of light metal, such as aluminum. In this construction particular importance is attached to the material concentration in extruded sections and to the support against two sliding surfaces in the region of the flange-like upper web.

A desirable feature of the invention provides a girder of a plastics material. A girder in accordance with the invention may be produced, for example, of a material based on polyvinyl chloride. Preferably a material formed of PVC or PVC based polymers is used. The invention moreover concerns other suitable plastics materials too such as, for example, polystyrene. It is also advantageous to use a plastics material based on polyamide.

The invention herewith provides advantageously an insert of material considerably resistant to extension, such as steel in the material concentrations in the lower flanges of the outer and the inner girders. When using plastics material for the construction it is advantageous for the inner girder to be substantially shaped as an isosceles triangle arranged with the acute angle pointing downwards, the inner space thereof being divided by means of honeycomb-like arranged webs.

The invention will be described further, by way of example, with reference to the accompanying drawings in which:

FIG. 1 is a cross-section through an outer girder in accordance with the invention;

FIG. 2 is a cross-section through a cooperating inner girder in accordance with the invention;

FIG. 3 is a cross-section through an inner girder constructed of a plastics material, for an outer girder section in accordance with FIG. 1.

FIG. 4 is a fractional view through the outer girder to show the lower web which may be constructed of plastics material;

FIG. 5 is a view of an arrangement of the inner and outer girder shown in cross section on the line V—V in FIG. 6;

FIG. 6 is a side elevation of the girder in accordance with FIG. 5; and

FIG. 7 is a force diagram shown schematically and only partly for a girder construction in accordance with FIG. 5.

The outer girder shown in FIG. 1 has a profile which, in the operational position, is constructed substantially in

the form of an inverted U having webs 1, 2 tapering downwardly inwardly. The webs are constructed as solid-webbed elements but they may be perforated. On their upper ends the webs are connected by means of an upper flange 3. At their lower ends the webs have concentrations 4, 5 of material whose inner surfaces 6, 7 are substantially parallel and serve as guides for the lower web of the inner girder still to be described.

It is evident that the webs 1, 2 at their upper ends are connected with the upper flange 3 by means of concentrations of material 8, 9. The outer sides 10, 11 of these sections are preferably inclined relative to the longitudinal centre plane which is indicated by the line 12 thus causing it to form an obtuse angle relative to the webs 1, 2 and the upper flange 3. The concentrations 8, 9 protrude into the interior of the girder. These material concentrations have substantially vertical wall sections 13, 14 extending downwardly from the upper flange 3 and wall sections 15, 16 sloping obliquely downwardly to the outside in continuation of the sections 13, 14. The wall sections 15, 16 always assume the same angle relative to the horizontal.

The material concentrations 8, 9 are together greater than the material concentrations 4, 5 in the lower flange. The described profile may be produced by extrusion, it being possible to provide cambers of girder.

The drawn-in open side of the outer girder profile is bridged over by at least one U-shaped stirrup 17 which engages over the outer sides of the material concentrations 4, 5 and may be secured by means of screw bolts 18, 19 to the material concentrations. It is possible to use threaded insert bushes 59, 60, for these bolts so that small dimensions may be obtained when using a comparatively soft material. If necessary, the U-shaped stirrup 17 may be attached by welding.

The material concentrations 8, 9 are spaced from one another substantially by the width of the girder. This provides a good rigidity laterally. The distribution of the material concentrations in the upper and lower flanges moreover provides a high load-bearing capacity for the girder in relation to the quantity of material used.

FIG. 2 shows an embodiment of an inner girder for use with the outer girder of FIG. 1. This inner girder has a Y-shaped web portion 20 on the vertical web of which there is arranged at the bottom a material concentration 21 and at the top outer edges thereof concentrations 21 and 23 which have a corresponding effect to the material concentration of the outer girder. The material concentrations 22 and 23 in the region of the outer ends of the upper flange 24 and the upper ends of inclined webs 25, 26 have sliding surfaces 27, 28 corresponding to the surfaces 15, 16 and also vertical limiting surfaces 29, 30. The distance between the surfaces 29, 30 is smaller than the distance between the surfaces 13, 14. The angle of inclination of the surfaces 27, 28 corresponds to that of the surfaces 15, 16. The height of the surfaces 13, 14 is preferably less than that of the surfaces 29, 30. This ensures that the load transfer is effected via the surfaces 15, 27 and 16, 28 simultaneously centering the inner girder between the surfaces 13 and 14.

The material concentration 21 is formed as a bead and for reasons still to be described is provided preferably with a downwardly rounded surface 31. The profile in accordance with FIG. 2 may be produced by extruding.

The profiles according to FIGS. 1 and 2 may be produced of steel, or of light metal or of a plastics material. When produced of a plastics material, a construction according to FIGS. 3 and 4 is preferred, of which FIG. 3 shows a modified form of inner girder. It is pointed out that the inner girder in accordance with FIG. 2 may also be made of plastics material, whereby in that case, as far as possible, an insert 61 resistant to extension is

arranged in the manner yet to be described in the region of the lower material concentration 21.

The profile in accordance with FIG. 3 consists substantially of an isosceles triangle, the acute angle of which faces downwards and extends into a comparatively wide web 32. Between the lateral webs 33, 34 and also the flange-like upper web 35 there are arranged honeycomb-like intermediate webs which, for example, in the upper region comprise a hexagonal honeycomb 36, intermediate webs 38, 39, 40 and 41 extending from the corners to the side webs 33, 34 and one intermediate web 42 extending downwards and which is forked to engage with the side webs 33, 34. Attention is drawn to the fact that an alternative intermediate web arrangement is also possible within the scope of the invention. The object of the arrangement of intermediate webs is to serve as a central support of the individual webs for the purpose of increasing the resistance to denting when constructing of comparatively soft materials. The upper region of web 32 is provided with a hollow space 43. In its lower portion it has an insert 44 resistant to extension. The insert resistant to extension is preferably made of steel and is profiled to obtain a good adherence. It is possible, for example, to use transversely ribbed steel, I-steel, twisted steel strands and the like which at all points ensure an adhesive bond in longitudinal direction between the material in the lower region of the web 32 and the insert. Attention is drawn to the fact that it is also possible to provide corresponding inserts possible of different dimension in special embodiments also in the region of the material concentrations at 45 and 46. These material concentrations are accordingly profiled at their outer surfaces with the surfaces corresponding to the surfaces 27 to 30.

In the construction of plastics material the outer girder, which is adapted to have a cross-sectional shape in accordance with FIG. 1, is provided in the region of its lower material concentrations 4, 5 preferably with inserts 47, 48 corresponding to the insert 44. It is possible then, for example, to provide equally or weaker profiled inserts also in the material concentrations 8 and 9 in accordance with FIG. 1.

Attention is drawn to the fact that a feature of girder construction with inserts consists in that the inserts are rigidly connected to supporting brackets or end pieces made of stronger material than the remaining girder portions. The end pieces, for example, may consist of steel.

FIG. 5 shows an assembly of the girders according to FIGS. 1 and 2. It is perceptible that the inner and outer girder are supported one against the other in the region of the inclined surfaces 15, 16 with 27, 28. The wedge-section-like abutment of these surfaces thus at the same time ensures centering of the girder portions in the region of the flange-like upper web 3, 24, thus causing the surfaces 13, 29 or 14, 30 to be guided without pressure on one another. The stated height dimensions of the surface 13, 14 relative to the surfaces 29, 30 thus ensure that also the flange-like upper web 3, 24 are caused to abut against one another with the surfaces facing one another without pressure or slight pressure, preferably with a slight clearance.

It is moreover perceptible from FIG. 5 that between the material concentrations 4, 5 at the lower ends of the lateral webs of the outer girder there is provided a cotter 49 indicated only in the drawing, for the purpose of locking the inner girder and outer girder by pressing the surfaces 27, 28 against the surfaces 15 and 16. The cotter is expediently of wide construction to cause it to abut with its sides against the surfaces 6, 7 of the material concentrations 4, 5. Thus shearing stress of the U-shaped stirrup 17 will be prevented if the cotter jams when it is driven home. The rounded construction of the lower surface 31 at the lower material concentration of the inner girder thus abuts against a cor-

respondingly formed concave recess 50 at the upper surface of the cotter, the rounding permitting momentarily an adjustment by alignment between the surfaces 15, 27 or 16, 28.

FIG. 6 by way of a side elevation shows a girder according to FIG. 5. The girder construction in accordance with FIG. 6 only comprises an inner girder 51 and an outer girder 52. Identical parts as in FIG. 5 are designated by the identical reference numerals. The outer ends of the girder portions are each provided with supporting brackets 53, 54. These supporting brackets may consist of steel. More especially when using inserts in accordance with FIGS. 3 and 4 it is possible, as shown in broken lines at 55 and 56 of the drawings, that such inserts may be extended beyond the lower chord of the corresponding girder portions when a fixing of the inserts to the supporting brackets is provided.

FIG. 7 shows the schematic force distribution by transmitting the loading forces via the surfaces 15, 16 or 27, 28, which are shown in FIG. 7 of the drawing. The forces transmitted via these surfaces extend vertically relative to these surfaces and each have a resultant corresponding to the arrows 57, 58 or 59, 60.

For the inner girder it is perceptible that the resultant 59, 60 is composed of the components 61, 62 or 63, 64. The components 62, 64 cause the flange-like upper web 24 to be impinged upon with compressive forces corresponding to the arrows shown in the drawing. The construction with the surfaces 27, 28 below the plane of the flange-like cross-girder 24 thus according to the proportion of the vertical distance between these surfaces and the plane of the upper web produces a bending moment, the magnitude alongside the width of the flange-like upper web 24 depends upon the components 61, 63. It is therefore evident that by inclining the surfaces 27, 28 the kind of loading the flange-like upper web 24 can be selected, this inclination however having to be selected expediently in such a manner that the compressive forces shown in the drawing occur in this upper web.

Compressive forces also occur under the circumstances shown in the webs 25, 26. It is understood that the force distribution depends not only on the inclination of the surfaces 27, 28 but also upon the angle 66 between the webs 25 and 26 and adapted to be selected for the production.

The outer girder in accordance with corresponding considerations absorbs in the flange-like upper web 3 and also in the first webs 1, 2 tensile forces according to the arrows shown in the drawing.

With regard to the construction of plastics material, for example, the sliding surfaces on the outer or inner girder may be metallized. Moreover the invention also provides combined girder constructions, according to which the outer and inner girders are made of different materials. For example, the inner girder wherein an insert is provided in at least the lower material concentration is adapted to be made of plastics material, whilst the outer girder is made of metal.

What I claim is:

1. A telescopic girder construction comprising at least one outer girder section and at least one inner girder section adapted to be telescoped one into the other, and means for locking the girder sections together, the outer girder section including a transverse upper web and side webs extending downwardly from the edge portions of said transverse upper web, characterized by the provision of inclined plane bearing surfaces at the inside corners where the upper web is joined to the side webs, the inner girder section including a transverse upper web and side webs extending from edge portions thereof, the upper corners of the inner girder section having slidably engagement with said inclined plane bearing surfaces of the outer girder section, and a clearance being provided between the transverse upper webs of the outer and inner girder sections.

2. A telescopic girder construction according to claim 1 in which the inner girder section has inclined plane bearing surfaces adjacent the area of slidable engagement between the two girder sections.

3. A telescopic girder construction according to claim 2 in which the angle of said inclined plane bearing surfaces is predetermined to produce compressive forces in said transverse upper web of the inner girder.

4. A telescopic girder construction according to claim 2 in which the angle of said inclined plane bearing surfaces to the horizontal is between 45° and 10°.

5. A telescopic girder construction according to claim 2 in which the angle of said inclined plane bearing surfaces to the horizontal is between 40° and 20°.

6. A telescopic girder construction according to claim 2 in which the angle of said inclined plane bearing surfaces to the horizontal is approximately 30°.

7. A telescopic girder construction according to claim 2 in which said outer girder section has thickened lower edges with longitudinally extending strengthening inserts embedded therein.

8. A telescopic girder construction according to claim 2 in which said inner girder section has a thickened lower chord with a longitudinally extending strengthening insert embedded therein.

9. A telescopic girder construction according to claim 2 in which supporting brackets are affixed to outer ends of the respective girder sections and at least one longitudinally extending strengthening insert is embedded in each girder section, said strengthening inserts being secured to the respective supporting brackets.

10. A telescopic girder construction according to claim 2 in which the inner girder section is substantially the shape of an inverted isosceles triangle with the base thereof forming a transverse upper web and in which the interior is divided by honeycomb-like arranged webs which support central regions of said transverse upper web and the side webs between their ends.

11. A telescopic girder construction according to claim 2 in which the inner girder section has a hexagonal honeycomb-web in the interior thereof and intermediate webs extending to said transverse upper web and side webs thereof, and an intermediate web bifurcated at its

40

end, the bifurcated ends of which are connected to the side webs in the lower region of said girder section.

12. A telescopic girder construction comprising at least one outer girder section and at least one inner girder section adapted to be telescoped one into the other, and means for locking the girder sections together, the outer girder section including a transverse upper web and side webs extending downwardly from the edge portions of said transverse upper web, characterized by the provision of thickened upper corner portions at the corners where the upper web is joined to the side webs, the inner girder section including a transverse upper web and side webs extending from edge portions thereof, the upper corners of the inner girder section having slidable engagement with said thickened corner portions of the outer girder section, the inner girder section having thickened upper corner portions adjacent the area of slidable engagement between the two girder sections, the outer girder section comprising inclined lower surfaces and substantially vertical surfaces extending upwardly from the inner edges of said inclined upper surfaces, the inclined surfaces of the two girder sections having a mating engagement and the opposed substantially vertical surfaces of the two girder sections having a clearance between them, the engagement of the inclined surfaces at the upper corners of the girder sections centering the inner girder section within the outer girder section.

13. A telescopic girder construction according to claim 12 in which the inner girder section has a transversely rounded lower edge engaging a complementary rounded surface of said locking means whereby the centering action of the inclined surfaces at the upper corners can take place with free alignment of the two girder sections.
